UNITED STATES PATENT OFFICE.

EDWARD CRAIG, OF ST. JOSEPH, MICHIGAN, ASSIGNEE TO SARANAC MACHINE CO., OF ST. JOSEPH, MICHIGAN, A CORPORATION OF MICHIGAN.

METAL-BOUND-BOX-END-STAPLING MACHINE.

1,205,329.

Specification of Letters Patent.

Patented Nov. 21, 1916.

Application filed June 16, 1910. Serial No. 567,186.

To all whom it may concern:

Be it known that I, EDWARD CRAIG, a citizen of the United States of America, and resident of St. Joseph, Berrien county, Michigan, have invented a certain new and useful Improvement in Metal-Bound-Box-End-Stapling Machines, of which the following is a specification.

My invention relates to machinery for making boxes or other like receptacles.

It contemplates broadly a machine that will staple the ends of a metal bound box, by inserting the staples through the sheet metal binding and into the end walls of the box, thus securing the end walls and sides of the box together.

Prior to my invention, it was not possible to staple the ends of a box of this particular character, as it was not known, until demonstrated by me, that wire staples could be driven through the metal binding of this box.

It is also an object, of course, to provide certain details and features of construction and combinations tending to increase the general efficiency and desirability of a metal-bound box-end-stapler of this particular character.

In the accompanying drawings—Figure 1 is a side elevation of a metal bound box end stapling machine embodying the principles of my invention. Fig. 2 is a detail plan view, on a larger scale, of the end portion of the arm or rest upon which the box is supported while being stapled. Fig. 3 is a front elevation of the machine shown in Fig. 1. Fig. 4 is a perspective of the so-called simplex metal bound box, the ends of which are stapled by my improved machine. Fig. 5 is a detail section, on an enlarged scale, on line 5—5 in Fig. 4. Fig. 6 is a detail section on line 6—6 in Fig. 5. Fig. 7 is an enlarged side elevation of the front portion of the said machine. Fig. 8 is a vertical section on line 8—8 in Fig. 7, showing some of the elements in elevation. Fig. 9 is a plan of the machine shown in Fig. 1. Fig. 10 is a detail view of the feed mechanism, being in the nature of a section on line 10—10 in Fig. 9. Fig. 11 is a vertical section on line 11—11 in Fig. 10.

As thus illustrated, my invention comprises an upright standard or pedestal A

upon the upper ends of which are rigidly mounted the laterally and substantially horizontally projecting arms B and C, whereby the various operative elements are supported in suitably elevated positions. A horizontal shaft D extends longitudinally within the arm B and is provided at its outer end with a driving pulley d which is governed by a clutch d' controlled by a foot lever d" in the usual and well known manner.

The stapling head E is mounted in an upright manner at the outer end of the arm B, and comprises the well known staple former e, the usual staple driver e', and the loop bar e", together with a lock e⁸ for automatically locking and unlocking the staple former, all constructed and operated in the well known manner. The staple driver e' is secured to one side of the vertically reciprocating head e⁴, which latter is provided with vertical guide rods e⁵ that move up and down in the outer end portion or stationary head e⁹ of the arm B, and which is actuated by a crank connection e⁷ with the driving shaft D. The stationary head e⁹ has a hollow portion e⁸ at one side thereof, which provides the usual housing for the staple former and staple driver, and for the loop bar, which latter is pivoted at e⁹ and controlled by the cam e¹⁰ on the back of the staple driver. A link e¹¹ is pivoted on the upper end of the staple former e, and provided at its lower end with a finger e¹², which latter is adapted to be inserted between the points of the staple, when the latter strikes the sheet metal binding, as will hereinafter more fully appear. A rod e¹³ has its lower end pivoted to the link e¹¹, and has its upper end held for vertical reciprocation in the guide plate e¹⁴, which latter is secured to the vertically reciprocating head e⁴. The rod e¹³ has a collar e¹⁵, and a spring e¹⁶ is interposed between this collar and the bottom of the plate e¹⁴, whereby spring pressure is always exerted downward upon the staple former e. The lock e⁸ is pivoted on the staple driver, and a cam e¹⁷ is provided on the casing of the stapler to engage the said lock at the proper time and thereby disengage it from the staple former, thus permitting the staple driver to continue its downward movement after the staple former engages the surface of the sheet metal.

binding through which the staple is to be inserted. The short length of wire is bent upon the loop bar c^2 , by the downward movement of the slotted or bifurcated staple former c , in the usual manner.

When the staple is fully formed, the staple former engages the surface of the sheet metal binding, and at the same time the finger e^{12} enters the slot e^{18} in the face 10 or cover plate e^{19} of the stapler. The spring e^{16} causes the finger e^{12} to engage between the points of the staple, and thus the latter are supported and prevented from being bent or deflected toward each other. 15 Then the pivoted lock e^3 strikes the cam e^{17} , thus unlocking the staple former, and permitting the staple driver to continue its downward movement alone. In this way the staple is inserted through the metal 20 binding of the box, as shown in Figs. 4, 5 and 6, and when the top of the staple strikes the beveled or rounded end of the finger e^{12} , the latter is thereby thrown outward to permit the complete insertion of the staple. 25 The wire for the staples is carried on a reel F , and is fed through a feed tube f near the bottom of the stapler head. This is done by the feed rolls f^1 and f^2 , which are mounted upon the flange or plate f^3 , that 30 extends from one side of the stationary head e^6 , and which is integral therewith. These feed rolls can be of any suitable character, and regulated in any suitable manner, but the upper roll f^2 is preferably provided with 35 a shaft f^4 which extends through the plate f^3 , and which has a ratchet wheel f^5 inside of said plate. The ratchet dog f^6 is pivoted on the plate or arm f^3 that swings on the shaft f^4 , and which is operated by the pitman or reciprocating rod f^7 . This pitman 40 or rod has its other end suitably mounted upon the upper end of a swinging arm or link f^8 , and provided with a roll f^{10} adapted to engage a cam f^{11} on the drive shaft. The 45 spring f^{12} tends to keep the roll f^{10} pressed tightly against the face of said cam. The rotation of the said shaft D causes the cam f^{11} to reciprocate the rod f^7 , thereby causing an intermittent actuation of the shaft f^4 by the ratchet wheel and pawl f^5 and f^6 , to in 50 turn produce an intermittent feeding motion of the wire to the stapling mechanism. It will be readily understood that this feeding mechanism can be properly adjusted or timed in its operation to feed the wire at the proper time to the stapler. Thus the wire is fed by mechanism operated directly by the driving shaft.

The arm C supports the box while it is being stapled. The method of doing this is as follows: The sides and end walls of the box are placed in position, as shown in Fig. 4, but with one side of the box left open, as by allowing one side wall to swing loosely 55 to serve as a cover. The box is then placed

in position below the stapler, with the arm C inside of the box, and with the end wall G resting horizontally upon the said arm. At its outer end the said arm, which stands somewhat obliquely to the shaft D , when viewed from above, as shown in Figs. 2 and 9, is provided with a clench block H that is round when viewed from above, as shown in Fig. 2, and which serves to clench the staples in the manner shown in Fig. 6. This clench block is mounted at the upper end of a screw-threaded stem h , which latter is mounted in a threaded opening in the end of the arm C , and provided with a lock nut h' , whereby the clench block can be adjusted 70 up and down and retained in any desired position. The top of said clench block has a circular groove or recess h^2 whereby rotation of the clench block does not interfere with the clenching of the staples, as such clenching will obviously be accomplished regardless of the position to which the clench block is rotated or adjusted up and down. It will be seen, however, that this clench block can be elevated so that it projects slightly above the upper surface c of the arm C , as shown in Figs. 1 and 7 and 8, whereby its curved or cylindric surface is exposed at all sides thereof. With this provision, the inner surface of the sides of the 75 box can be held tightly against the clench block and the box moved along during the driving of the staples, the clench block in this manner serving also as a gage for determining the position of the box below the 80 stapler, whereby the staples will be driven successively in rows along the metal binding g , which latter extends along the edges of the end wall of the box.

It will be seen that the staples are thus 85 driven at a uniform distance from the flange or upper edge g' of the said metal binding, such flange inclosing and protecting the end edges of the side walls g^2 , as shown more clearly in Fig. 5. One side of the box is 90 moved along in one direction to drive one row of staples, the inner surface of such side being held tightly in engagement with the clench block to keep the staples a uniform distance from the flange g' , as shown 95 in the drawings; then when the corner of the box is reached, the next side thereof is moved along in another direction, with the inner surface thereof held tightly in engagement with the clench block, to drive the 100 next row of staples; and the third row of staples is then driven in a similar manner. The third or loose side of the box, which is to serve as a cover, is not stapled to the end walls. Thus no matter which way the 105 box is turned or moved, the clench block H always presents a rounded side to the inner side surface of the box to keep the staples a uniform distance from the side of the box. Thus the said clench block serves as a con- 110

bined anvil or clenching device and gage for determining the position of the box on the arm C. It will be understood that the box is thus manipulated by hand. In another form of the said box, in which a slide cover is used, one side of the box is left open, but the binding is stapled at all four sides—that is to say, at all four edges of the end wall,—because when a slide cover is used the metal binding for the open side of the box must be secured to the end walls thereof. The stapling in such case is accomplished by raising the clench block H slightly above the upper surface of the arm C, whereby it is adapted to engage the inner edge, or more properly speaking the lower edge, of the binding at the open side of the box. In other words, the staples in such case are driven by causing the clench block to successively engage the three side walls g^2 , as in the previous case; but when the operator comes to the open side of the box, then the only way in which an accurate driving of the staples can be accomplished is by keeping the lower edge of the binding at that side in engagement with the clench block, and by causing the binding to slide along the said clench block, until staples are driven for the full length thereof. The recess or notch e' in the side of the arm C is adapted to engage or receive one of the open edges of the box at this time to permit the staples to be driven close to the corner, and the position of the box at this time is such that each staple is so driven that its top extends very nearly lengthwise of the strip of metal binding. At the other side of the box, the staples must, of course, be more or less oblique or crosswise of the binding. There are, however, different ways of manipulating the box on the arm C, and the notch or recess e' is provided simply to facilitate such manipulation, especially at one or more corners of the box in a manner that will be obvious and easily recognized by the user.

It will be seen the stapling mechanism is so disposed above the clench block H that the staples are driven with their tops on the line $z-z$ in Fig. 2, which line extends, of course, in the direction in which the wire is fed. The machine is what may be called a deep throat stapler, inasmuch as the throat I, between the upper and lower arms, is very deep, and of a length to receive a large or wide end wall G, whereby either large or small boxes can be stapled. The finger e^{12} is a special provision, and is necessary, or at least highly desirable, in a machine of this kind, where the staples are to be driven through metal, and especially so when the staples are made from light wire. The clench block H, which is made round to serve as a gage for all four sides of the box, permits accurate stapling of the ends

of a box of this kind and has special reference to the manufacture of these boxes.

I claim, therefore, that I am the first to propose and construct an operative and practical machine of this kind, and for this particular purpose, which will accurately and with certainty insert the staples through sheet metal and then into softer material, such as wood, and for this reason I do not limit myself to the exact construction shown and described, so far as the broader purpose of my invention is concerned.

It will be seen that the extreme end portion of the arm C, in which the screw h is mounted vertically, is partially cylindric in form, being flush with the sides of the clench block H, thus permitting the said block to engage the inner surface of the vertical walls of the box. When the arm C is inserted in the box, the cylindric sides of the clench block H, and the rounded surface of the said arm immediately below the said block, will engage the inner surface of the sides of the box, permitting the latter to be easily turned or manipulated about a vertical axis to keep the side walls of the box in contact with said block and the extreme outer end portion of said arm.

What I claim as my invention is:

1. In a stapling machine, a shaft, a stapling head operated thereby and disposed in position to form and drive the staples in a plane parallel with the vertical plane of the said shaft, a wire feed mechanism for said stapling head, a cam on said shaft, a rod operated endwise by said cam to actuate said feed mechanism and disposed lengthwise of said shaft, and a support below said shaft for the work, said feed mechanism having an axis extending crosswise of said shaft, whereby the staples are driven in a vertical plane extending longitudinally of the said shaft and support. 95

2. In a stapling machine, a horizontal shaft, a stapling head at one end of said shaft, disposed in position to form and drive the staples in a plane parallel with the vertical plane of the said shaft, an arm supporting and inclosing the middle portion of said shaft, a cam at the other end of the shaft, a wire feed mechanism for said stapling head, a rod disposed substantially horizontally and operated endwise by said cam to actuate the feed mechanism, said stapling head and feed mechanism being supported on the end of said arm, and a support below said shaft for the work, said feed mechanism having an axis extending crosswise of said shaft, whereby the staples are driven in a vertical plane extending longitudinally of the said shaft and support. 110 115 120 125

3. In a stapling machine, a staple former, a loop bar, a staple driver, staple supporting means on the staple former arranged to 130

extend between the points of the staple, and a spring connection between the said means and the driver.

4. In a stapling machine, a staple former, a loop bar, a staple driver, an element pivoted on the staple former and arranged to extend between the points of the staple, and a spring connection extending to said element to control the same and yieldingly 10 hold the said former on the work.

5. In a stapling machine, movable elements for forming and driving the staple, means to move said elements down, means disposed on one of said elements and arranged to extend between the points of the staple during driving of the latter, and a device connected with said means to hold the said one element down.

6. In a stapling machine, a staple former, a loop bar, a staple driver, an element pivoted on the staple former arranged to extend between the points of the staple, a head for operating the said driver, a spring connection from the head to said element to both yieldingly control said element and hold said former down, and means for automatically locking the staple former to and unlocking it from the staple driver.

7. In a stapling machine, a clench block made round to serve as a gage for the four sides of the box, means for adjusting and holding the block stationary while the sides of the box are successively brought into contact with the different sides of the block, a support for said block, adapted to enter the box and permit manipulation of the box in direct contact with the sides of the block, and means for inserting fastening devices and driving them against said block.

8. A stapling machine for securing the heads in metal bound boxes, comprising a support for insertion in the box, said support including an arm adapted to enter the box, a cylindric clench block at the end of said arm, the axis of said block being vertical, a stem for said block, and means for adjusting said stem vertically to raise and lower said block, said block being disposed at the extreme end of said arm to engage 50 the sides of the box to determine the position of the staples along the edges of the head of the box.

9. A stapling machine for securing the heads in metal bound boxes, comprising a support for insertion in the box, said support including an arm adapted to enter the box, a cylindric clench block at the end of said arm, the axis of said block being vertical, a stem for said block, and means for

adjusting said stem vertically to raise and 60 lower said block, said block being disposed at the extreme end of said arm to engage the sides of the box to determine the position of the staples along the edges of the head of the box, said means including a 65 head on said stem and screw-threads in said arm to engage the stem, and a lock-nut on said stem.

10. A stapling machine for securing the heads in metal bound boxes, comprising a 70 support for insertion in the box, said support including an arm adapted to enter the box, a cylindric clench block at the end of said arm, the axis of said block being vertical, a stem for said block, and means 75 for adjusting said stem vertically to raise and lower said block, said block being disposed at the extreme end of said arm to engage the sides of the box to determine the position of the staples along the edges 80 of the head of the box, said block extending above the top of said arm to expose its entire circumference for engagement with the box.

11. A stapling machine for securing the 85 heads in metal bound boxes, comprising a support for insertion in the box, said support including an arm, a cylindric clench block at the end of said arm, the axis of said block being vertical, a stem for said 90 block, and means for adjusting said stem vertically to raise and lower said block, the sides of said block engaging the box to determine the position of the staples, said arm being notched at one side thereof to 95 facilitate positioning the box on said block.

12. A stapling machine for securing the heads in metal bound boxes, comprising a support for insertion in the box, said support including an arm adapted to enter the 100 box, a cylindric clench block at the end of said arm, the axis of said block being vertical, a stem for said block, and means for adjusting said stem vertically to raise and lower said block, said block being disposed at the extreme end of said arm to engage 105 the sides of the box to determine the position of the staples along the edges of the head of the box, said arm having a rounded end portion in alignment vertically 110 with the sides of said block.

Signed by me at St. Joseph, Mich., this 27th day of May, 1910.

EDWARD CRAIG.
